CLAIM

The ornamental design for a liquid measuring vessel, as shown and described.

DESCRIPTION

FIG. 1 is a top, front and left side perspective view of a liquid measuring vessel showing our new design;

FIG. 2 is a left side elevation of the liquid measuring vessel, the right side elevation is a mirror image thereto except for the threading;

FIG. 3. is a front elevational view thereof;

FIG. 4. is a rear elevational view thereof;

FIG. 5. is a top plan thereof; and,

FIG. 6. is a bottom plan view thereof.

The broken lines showing a bottle in FIG. 1 are for illustrative purposes only and do not form part of the claimed design.
